BOBBIN TRANSFER MECHANISM

Karol Kulczycki, Brooklyn, N. Y., assignor, by
mesne assignments, to Steel and Alloy Tank
Company, Newark, N. J., a corporation of New
Jersey

Application March 3, 1950, Serial No. 147,483

17 Claims. (Cl. 139—243)

1

The present invention relates to automatic filling transfer mechanisms for looms.

In the usual type of automatic loom of the fly shuttle type, there is provided a rotary hopper or battery operable to automatically replenish the filling. The reserve filling carriers or bobbins are held at their heels and tips by and between two discs of this hopper and are arranged therein in a circular series. The hopper is rotated step by step in a feed direction automatically through an indexing device to successively position the bobbin at the bottom of the hopper against a combined stop and bobbin ejector guide for transfer to the shuttle. The stop is so located that it will check the lowermost bobbin to be transferred in the correct position for it to be forced out of the hopper and into the shuttle.

In prior art constructions, the indexing device may be released to permit the hopper to be manually rotated in a feed direction. However, the bobbin stop associated with the hopper permits manual rotation of the hopper only to the extent to which the hopper is unfilled as the hopper will always stop when a bobbin reaches said stop.

In the usual transfer mechanism, there is located near the bottom of the hopper a main transfer arm disposed between the two rotary hopper discs and adapted to engage the heel of the lowermost bobbin upon transfer and an auxiliary transfer arm constituting a rigid extension of said main transfer arm and also extending between said discs to engage the tip of said lowermost bobbin upon transfer. The resulting blocking of the lower section of the hopper, plus the presence of a stop in the way of the lowermost bobbin makes it impossible to rotate the hopper continuously in one direction upon the release of the indexing or feed device for manual control. As a result, the filling of the hopper is most difficult to accomplish from the front of the loom.

One object of the present invention is to provide a new and improved bobbin transfer mechanism, which permits the hopper to be rotated continuously at least in the feed direction, regardless of the number of bobbins on said hopper, when the hopper indexing or feed device has been released for manual control and which permits thereby the easy filling of the hopper entirely from the front of the loom.

Another object of the present invention is to provide a new and improved bobbin transfer mechanism, which is operable to effect smooth transfer of the bobbin with minimum of shock, which is positive, accurate and instantaneous in its operations and reactions, and which has mov-

2

able bobbin transfer parts in position to avoid spoilage of the bobbins through the lubricant carried by said parts.

Various other objects of the invention will be apparent from the following particular description and from an inspection of the accompanying drawings, in which:

Fig. 1 is a fragmentary perspective of the right hand side of the loom and shows a filling transfer mechanism embodying the present invention;

Fig. 2 is a rear view of the loom taken approximately along the lines 2—2 of Fig. 1;

Fig. 3 is a section of the loom taken approximately along the lines 3—3 of Fig. 2, but showing the transfer mechanism in position before transfer is indicated;

Fig. 4 is an enlarged longitudinal section of the auxiliary transerrer shown in full lines in operative position and in dot and dash lines in inoperative position;

Fig. 5 is an enlarged longitudinal view partly in section of an extensible link connection employed in conjunction with the main and auxiliary transerrers and the shuttle feeler;

Fig. 6 is a section of the loom similar to that of Fig. 3, but showing the transfer mechanism when transfer is called for after clearance by the shuttle feeler and at the instant the lowermost bobbin in the hopper is beginning to be ejected from said hopper towards the boxed shuttle;

Fig. 7 is a section of the loom similar to that of Fig. 3, but showing the transfer mechanism at a later stage, after the bobbin has been transferred into the shuttle;

Fig. 8 is a section of the loom taken approximately along the lines 8—8 of Fig. 2 and showing the transfer mechanism after transfer is called for but at the instant the shuttle feeler is being operated by an improperly boxed shuttle, to revoke the transfer call;

Fig. 9 is a section of the loom similar to that of Fig. 8, but showing the transfer mechanism at a later stage in the front center position of the lay;

Fig. 10 is an enlarged detail section of the shuttle feeler; and

Fig. 11 is an end view of the shuttle feeler.

Referring to Figs. 1, 2 and 3 of the drawings, the reserve bobbins 10 on which the filling yarn is wound are carried in a circular series in a rotatable hopper or magazine 11. The hopper 11 is on the right-hand side of the loom and comprises a stationary plate 12 secured to a hopper stand 13 affixed to the right loomside 15. The hopper stand 13 carries a bearing support 16 for

a hopper shaft 17 to which a pair of axially spaced bobbin supporting discs is affixed for rotation in unison, only the inner one of said discs 18 being shown. The connection between the two rotatable bobbin supporting discs and the shaft 17 may comprise a long hub 20 having a key connection with said shaft. The hub 20 may be integral or otherwise rigid at one end with the outer bobbin supporting disc (not shown) and may be provided at its other end with a coupling flange 22 secured to the outer disc 18 by studs 23.

Connected directly to the outer side of the outer bobbin supporting disc (not shown) may be a suitable peripherally notched thread guide (not shown) cooperating with a thread holder (not shown) in a manner known in the art.

For releasably supporting the heels or butts of the bobbins 10 in the inner disc 18, said disc has a ring 30 in its outer periphery secured to the body of the disc by studs 31 and having a series of circumferentially spaced peripheral recesses 32 in which the heels of the bobbins 10 are inserted. The heels of the bobbins project beyond the inner disc 18 outside of the space between the two bobbin supporting discs.

For releasably supporting the tips of the bobbins in the outer supporting disc (not shown), said disc has a ring with a series of peripheral recesses 32 in the disc 18. A circular series of rods 33 within the circle of the bobbins 10 rigidly connect this ring with the ring 30.

With the arrangement described, the bobbins are supported with their heels or butts extending between the stationary plate 12 and the 35 rotary disc 18.

The hopper device so far described, forms no part of the present invention, and may be of any other well-known construction.

The operation of the transfer mechanism is controlled by a starting rod 40 supported in journals 41 on the right loomside 15. Whenever substantial exhaustion of the filling is indicated by a feeler (not shown) located to feel the bobbin when in the left box of the loom, a partial revolution is given to the starting rod 40 as the shuttle moves to the right box of the loom. This sets the transfer mechanism for transfer.

The actual transfer of the lowermost filled bobbin 10 in the hopper 11 is effected by a main transferrer 44 and an auxiliary transferrer 45 operable in unison by the motion of the lay 42 to engage the heel and a section of said bobbin near the tip respectively and to force said bobbin out of the hopper and against the spent bobbin in the shuttle 43. The filled bobbin, in being pressed into the top of the shuttle 43, forces the empty bobbin therein out through the bottom of the shuttle and into a suitable receptacle (not shown). By engaging the filled bobbin with the two transferrers 44 and 45 at spaced sections therealong for transfer, tilting is avoided and proper setting of the bobbin in the shuttle 43 is assured.

The main transferrer 44 comprises an arm 50 pivotally mounted on a stud or pin 51 on the hopper stand 13 and located outside the hopper 11 beyond the stationary plate 12. The transfer arm 50 has a transverse extension 52 (Figs. 1 and 2) passing through a slot 53 in the stationary plate 12 and terminating at its outer end in a shoe or head 54 between the plate 12 and the rotary disc 18 and adapted to engage

the heel of the lowermost bobbin 10 in the hopper 11 during transfer.

The auxiliary transferrer 45 comprises an arm 57 extending into the space between the two 5 rotary bobbin supporting discs of the hopper 11 and mounted on a hollow shaft 58. The shaft 58 is mounted for rocking movement on a bearing or axle rod 60 affixed to a support 61 integral or otherwise rigid with the hopper stand 13. The auxiliary transfer arm 57 has its inner 10 end, head or shoe 62, designed to engage the filled bobbin 10 to be transferred at a section thereof near the tip and is mounted on the rock-shaft 58 in a manner to permit it to be withdrawn from operative position outside of the ambit of the bobbin circle and to allow thereby the hopper 11 to be rotated continuously in a feed direction (clockwise Fig. 3), when the hopper is released from automatic index or feed control. To that end, the rock-shaft 58 has secured thereto an offset bracket 63 carrying a tubular holder 64 for the auxiliary transfer arm 57. The transfer arm 57 is slidable in the holder 64 and is releasably retained in operative transfer position shown in full lines in Fig. 4 by a spring-pressed ball device 65. A finger ring 66 at the outer end of the transfer arm 57 permits manipulation of said arm in and out of operative position. A pin 67 (Fig. 3) on the transfer arm 57 prevents said arm from being pulled all the way out of the holder 64.

If the transfer of a filled bobbin from the hopper 11 to the shuttle 43 were to take place with the shuttle in such a position as not to receive the bobbin properly, it is very probable that parts of the transfer mechanism or the shuttle would be broken. This is especially true in those cases in which the shuttle 43 does not receive sufficient momentum from the picking motion to enter properly the box 39 or in which the shuttle is rebounding in the box for any reason. In either case, the shuttle 43 will project from the box 39.

To prevent transfer of the filled bobbin under the conditions indicated, there is provided a shuttle feeler device, shown in detail in Figs. 8-11 and comprising a tubular guide 70 secured to a bracket 71 affixed to and depending from the base 72 of the hopper stand 13. Slidable in the guide 70 is a feeler plunger 73. A pin 74 extending through the feeler plunger 73 and through diametrically opposed elongated slots 75 in the guide 70 is engaged at its outer projecting ends by the forked prongs of an arm 76 affixed to a suitably journalled pivot shaft 77. When transfer is indicated, the arm 76 is operated from the starting rod 40.

The feeler plunger 73 is constructed to permit adjustments in the position of the feeler tip 80 thereon and to permit adjustments in the stop position of said plunger in shuttle feeling position. For that purpose, the feeler plunger 73 comprises a rod-like piston 81 having end sections 82 and 83 with snug slide fit in the guide 70 and an intermediate section 84 of smaller diameter to reduce slide friction. The end section 82 has a screw 85 projecting beyond the end of the guide 70 and carrying a nut 86 serving as an adjustable stop for said piston in its shuttle feeling position. The end section 83 of the piston 81 is hollow and is internally tapped to receive adjustably the threaded shank of the feeler tip 80. A lock nut 87 on this shank holds the feeler tip 80 in position adjusted to accommodate for bobbins of different sizes.

The feeler end of the tip 80 has a front edge 90 which extends vertically, so that it does not lift the shuttle in feeler position, and has its upper edge 91 curved to permit the filling end to pass easily thereover.

The feeler plunger 73 is operated from the starting rod 40 through the pivoted arm 76 when transfer is indicated. For that purpose, the starting rod 40 has rigidly connected thereto a crank arm 95, pivotally connected at its outer end to one end of a link 96, the other end of said link being connected at 97 to the pivoted arm 76.

For operating the transferers 44 and 45 for bobbin transfer when transfer is indicated and to effect protection through operation of the shuttle feeler device, there is provided a bell crank 100 pivoted at 101 to an extension 102 of the bracket 71 and having two arms 103 and 104. The crank arm 103 is connected to the main transfer arm 50 by a link 105 pivotally connected at its ends to said arms respectively. The other crank arm 104 pivotally carries a latch finger 106 adapted to be engaged by a bunter 107 on the forward side of the lay 42 during the forward movement of the lay, after transfer has been indicated and the shuttle feeler has cleared the mechanism for transfer. The bunter 107 has a V-shaped groove 108 and the outer end of the latch finger 106 is correspondingly bevelled for retention into said groove during transfer. The bottom of the bunter 107 is hollow to accommodate the latch finger 106 in the inactive position thereof.

The latch finger 106 is moved in and out of protective position through the feeler slide movement of the feeler plunger 73 in the guide 70. For that purpose, there is a spring connection 110 between the latch finger 106 and the feeler plunger 73. This spring connection, shown in detail in Fig. 5, comprises an extensible link in the form of two axially aligned rods 111 and 112 yieldably held together by an embracing coil spring 113. The rod 111 has an eye at one end for pivotal connection to the pin 74 carried by the feeler plunger 73, and the rod 112 has a similar eye at one end for pivotal connection to the latch finger 106. The two rods 111 and 112 are of similar construction and have aligned axial holes 116 receiving an aligning pin 117. Part 118 of each rod 111 or 112 near its eye is spirally grooved to retain the corresponding end of the coil spring 113, while the end parts 119 of said rods beyond said grooved spring retaining parts are of reduced diameter, so as not to interfere with the expansion and contraction of said spring.

The spring link connection 110 is such, that when no transfer is indicated, and the feeler plunger 73 is in the withdrawn inactive position shown in Fig. 3, the latch finger 106 is held by said link connection in depressed position out of the reciprocating movement of the bunter 107. When transfer is indicated, and the feeler plunger 73 has been moved into shuttle feeler position shown in Fig. 6, the latch finger 106 will be lifted into the path of movement of the bunter 107 by the spring link connection 110 to engage said bunter at its groove 108 when lay 42 moves forward towards front center position, thus transmitting the movement of the lay 42 to the bell crank 100. This bell crank rotating clockwise (Fig. 6), thereby swings the main transfer 44 through the link 105 about the axis of its pivot support 51 into bobbin transfer position.

For swinging the auxiliary transfer 45 into bobbin transfer position simultaneously with the main transfer 44, the link 105 has rigidly connected thereto intermediate of its ends a short transverse arm 125 pivotally connected at its outer end to one end of a short link 126, the other end of which is pivotally connected to the outer end of a crank arm 127 integral or otherwise rigid with the rock-shaft 58.

For effecting protection through operation of the shuttle feeler, the link 96 operated from the starting rod 40 through the crank arm 95 is of the giveaway or lost motion type to transmit motion to the pivoted arm 76 clockwise about its pivot support 71 into position shown in Fig. 8 when transfer is indicated and the starting rod 40 has been partially rotated and to yield without disturbing the rotative position of said starting rod when protection is indicated by the improper boxing of the shuttle, as shown in Fig. 9. To that end, the link 96 comprises a tube 130 having a head 131 threaded therein at one end and pivotally connected to the crank arm 95 and a head 132 threaded therein at the other end. Extending into the tube 130 and passing through the head 132 with a snug slide fit is a rod 133 having a pivot connection outside said tube with the pivoted arm 76. A coil spring 134 encircles the rod 133 in the tube 130 and bears at one end against a collar 135 pinned or otherwise affixed to said rod and at the other end against the head 132.

While the starting rod 40 is rotating from inoperative position to the transfer position shown in Fig. 8, and while the lay 42 is too far away to operate the shuttle feeler, motion is transmitted from said rod to the pivoted arm 76 through the giveaway link 96 with minimum of tension on said link. Motion is therefore, transmitted through the giveaway link 96 without causing relative axial movement between the tube 130 and the rod 133 thereof. When protection is indicated requiring revocation of the transfer call, the improperly boxed shuttle engaging the feeler tip 80 during the movement of the lay 42 towards front center position, will move the feeler plunger 73 in the guide 70 towards the right (Fig. 9), causing counterclockwise rotation of the pivoted arm 76 about its pivot support 71. This rotation of the pivoted arm 76 is resisted by the starting rod 40 held against counterclockwise (Fig. 9) rotation. However, the lost motion connection of the link 96 permits this counterclockwise rotation of the pivoted arm 76. This movement of the pivoted arm 76 and corresponding movement of the feeler plunger 73 towards the right lowers the latch finger 106 into the inoperative position shown in Fig. 9, to revoke the transfer call which had previously caused said finger to move into transfer position shown in Fig. 8.

The hopper indexing or feeding device for automatically rotating the hopper 11 one step after each transfer operation and for bringing the next bobbin into transfer position, per se forms no part of the invention and may be of any suitable or well known type or may be of the type shown and described in copending application Serial No. 147,482, filed March 3, 1950. This indexing device comprises a ratchet gear 140 (Figs. 1 and 2) affixed to one of the bobbin supporting discs 18 and rotated one step each time by a spring biased pawl 141 operated through an arm 142 (Fig. 3) pivotally connected to the main transfer arm 50. The pawl 141 in the normal position (Fig. 1) holds ratchet gear 140 against

clockwise rotation. After transfer has been completed, the parts of the transfer mechanism are returned to their normal position shown in Fig. 3 through the recoil action of a coil spring 143 connected to the main transfer arm 50 and to the hopper stand 13. The return movement of the main transfer arm 50 into normal position shown in Fig. 3 permits the spring 141a, which biases the pawl 141 to rotate the pawl 141 clockwise one step, to bring the next bobbin into transfer position. A stop 144 secured to the hopper stand 13 is adapted to engage the main transfer arm 50 in returned normal position.

A spring biased stop pawl 145 (Fig. 1) pivotally supported on the stationary plate 12 engages the ratchet gear 140 and serves to hold the hopper 11 against counterclockwise rotation. Suitable handle means 147 (Fig. 1) enables the pawl 141 to be disengaged easily from the ratchet gear 140, when it is desired to turn the hopper 11 by hand, as when inserting fresh bobbins.

A shuttle feeler thread cutter 150 (Fig. 1) is attached to the outer end of the cantilever rod 60 beyond the rock-shaft 58 supported thereon. Whenever the transfer mechanism is placed into operation by the filling feeler motion, a thread of filling extends from the selvage of the cloth through the shuttle eye to the bobbin contained in the shuttle. When the fresh bobbin of filling is inserted in the shuttle, not only must the old bobbin be removed but the shuttle eye must be cleared to allow the yarn from the new bobbin to be properly threaded in the eye. To accomplish this, the thread extending from the selvage of the cloth must be cut as closely as possible to the shuttle, so that the old bobbin, in being ejected, will draw the short length of yarn left extending from the shuttle, through the shuttle eye, leaving the latter entirely clear and free.

The usual temple thread cutter (not shown) alone cannot accomplish this result, as it cuts the thread at too great a distance from the shuttle eye and it does not positively operate at the correct time. The thread cutter 150, however, not only severs the filling yarn close to the shuttle at the time of the transfer of filling, but also clamps and holds the end extending to the cloth, so that the temple thread cutter will again cut the yarn close to the selvage in the ordinary manner.

The thread cutter 150 per se forms no part of the present invention and may be of any well known type. The thread cutter 150 is shown operated from an arm 151 (Fig. 2) affixed to the pivot shaft 71 to which the arm 76 is attached and having a cable connection 152 to said thread cutter passing through a cable casing 153 (Fig. 1). At the end of each transfer, the thread cutter 150 is operated.

Operation

Although the operation of the transfer mechanism and the shuttle feeler is believed apparent from the foregoing description, this operation is herein summarized:

While the loom is normally operating and the yarn supply on the running shuttle is ample, the starting rod 40 will be in the rotative position shown in Fig. 3, the latch finger 106 will be depressed out of the path of the lay bunter 107 and the shuttle feeler plunger 73 will be withdrawn in its guide 70, as shown. In this position of the starting rod 40, the main and auxiliary transferrers 44 and 45 will be in elevated position directly above the lowermost bobbin 10 in the

hopper 11, with the head 54 of said main transerrer directly over the heel of said bobbin and the head 62 of said auxiliary transerrer over the section of said bobbin near its tip.

Upon the receipt of a transfer impulse from a suitable filling feeler mechanism near the left side of the loom indicating substantial exhaustion of the filling, the starting rod 40 will be partially rotated counterclockwise from the position shown in Fig. 3 to that shown in Fig. 6. This operation is effected while the lay 42 is moving towards the rear of the loom (towards the right in Fig. 6) and while the shuttle 43 is moving towards the box 39 on the magazine side of the loom, and causes the pivoted arm 76 to swing counterclockwise and the feeler plunger 73 just beyond the end of the shuttle 43 to be shifted in its guide 70 to the right. This movement of the feeler plunger 73 raises the latch finger 106 through the extensible connection 110 from its depressed inactive position shown in Fig. 3 to the raised operative position in the path of the lay bunter 107 shown in Figs. 6 and 8. As the lay 42 arrives at its rear-most position and begins its forward movement, the open end of the box 39 just beyond the tip of a properly boxed shuttle moves past the shuttle feeler tip 80, so that the feeler plunger 73 will remain in the projected position shown in Fig. 8, while the lay 42 moves toward front center position. Upon continued forward movement of the lay 42, the bunter 107 thereon will engage the raised latch finger 106, as shown in Fig. 7, and rotate the bell crank 100 clockwise about its pivot support 101, causing thereby depressing angular movement of the main transfer arm 50 clockwise about its pivot support 51 through the link 105 and depressing angular movement of the auxiliary transfer arm 51 clockwise about the rod 60 through the linkage 125, 126, 127. The extensibility of the link connection 110 through its spring 113 permits this clockwise rotation of the bell crank 100. The heads 54 and 62 on the transfer arms 50 and 51 respectively engaging the lowermost bobbin 10 in the hopper 11 will by these operations eject said bobbin from said hopper, while maintaining it horizontal. The filled bobbin is delivered into the shuttle 43 smoothly and with a final deceleration which imparts a minimum of momentum to the bobbin as it is engaged by the usual shuttle spring. The bobbin is deposited into the shuttle at such speed as to avoid the possibility of overthrowing the bobbin beyond the shuttle spring. As a fresh bobbin is being inserted into the shuttle as described, the spent bobbin is forced out of the shuttle by its engagement with the incoming bobbin and dropped into a suitable receptacle.

Upon return movement of the transferrers 44 and 45, the indexing device is operated by the arm 142 to automatically rotate the hopper 11 one step and to bring thereby the next bobbin therein in transfer position.

If after the starting rod 40 has been rotated counterclockwise into the position shown in Fig. 6, the extended shuttle feeler tip 80 during the forward movement of the lay 42 engages the tip of the shuttle 43, then the feeler plunger 73 will be forced forwardly by the engaging shuttle 43 into the guide tube 70, as shown in Fig. 9, causing thereby the latch finger 106 to be swung by the extensible link connection 110 downwardly about its pivot support on the bell crank 100 and out of the forward path of movement of the lay bunter 107. Under these conditions, as the lay 42 continues its forward movement, the bunter

107 misses the depressed latch finger 106 and the transfer impulse becomes ineffective. The transfer of a bobbin from the hopper 11 to the shuttle 43 cannot therefore take place.

It should be noted that no stops are provided for engaging the lowermost bobbin in the hopper 11, so that when the pawl 141 is moved into inactive position, the hopper may be rotated clockwise (Fig. 3) continuously regardless of the number of bobbins in said hopper, provided of course, the auxiliary transfer arm 57 has been withdrawn in its holder 64 into the dot and dash position shown in Fig. 4 out of the path of the bobbins in the hopper. The hopper may thereby be filled entirely from the front of the loom regardless of the number of bobbins in the hopper.

It should be noted that the main transfer mechanism is outside the field between the two rotary hopper discs, so that spoilage of the bobbins through the lubricant on said mechanism is avoided.

It should also be noted that the main and auxiliary transmitters in operative position occupy minimum of bobbin space near the bottom of the hopper. With this arrangement, a hopper containing space for 30 bobbins can be filled to hold and to operate with 29 bobbins, thereby increasing the capacity of the hopper over that of the prior art, in which a hopper containing space for 28 bobbins can only operatively hold 25 bobbins.

While the invention has been described with particular reference to a specific embodiment, it is to be understood that it is not to be limited thereto, but is to be construed broadly and restricted solely by the scope of the appended claims.

What is claimed is:

1. In a filling transfer apparatus for a loom, the combination comprising a rotary hopper having a pair of axially spaced rotary discs defining a circular series of stations for releasably holding the heels and tips of a number of bobbins between said discs, a main transfer mechanism for engaging the heel of a bobbin at the bottom of said hopper and ejecting said heel from said hopper towards a shuttle therebelow, said main transfer mechanism being located entirely outside of the space defined between said discs, an auxiliary transfer mechanism for engaging said bobbin near its tip and ejecting said tip from said hopper toward said shuttle, and means for operating said transfer mechanisms in unison.

2. In a filling transfer apparatus for a loom, the combination comprising a rotary hopper having a pair of axially spaced rotary discs defining a circular series of stations for releasably holding a number of bobbins between said discs with the heels of said bobbins projecting beyond one of said discs outside of the space between said discs, and with the tips of said bobbins releasably retained by the other disc, a main transfer mechanism for engaging the projecting heel of a bobbin at the bottom of said hopper and ejecting said heel from said hopper towards a shuttle below, an auxiliary transfer mechanism for engaging said bobbin near its tip and ejecting said tip from said hopper towards said shuttle, and means for operating said transfer mechanisms in unison.

3. In a filling transfer apparatus for a loom, the combination comprising a rotary hopper having a pair of axially spaced discs connected for rotation in unison, one of said discs having a series of circumferentially spaced recesses on its

periphery for receiving the heels respectively of a number of bobbins, the other disc having a similar series of circumferentially spaced recesses on its periphery in alignment with said heel receiving recesses respectively and adapted to receive the tips respectively of said bobbins, and a mechanism for transferring the bobbins successively from said hopper to a shuttle and comprising a main transfer shoe adapted to engage the heel of a bobbin in said hopper and to eject it out of its disc recess, an auxiliary transfer shoe adapted to engage said latter bobbin near its tip and to eject it out of its disc recess, and linkage means between said shoes for operating said shoes in unison for bobbin transfer.

4. In a filling transfer apparatus for a loom, the combination comprising a rotary hopper having a pair of axially spaced rotary discs defining a circular series of stations for releasably holding the heel and tip ends of a number of bobbins between said discs, and a mechanism for transferring the bobbins successively from said hopper to a shuttle and comprising a main arm, a main transfer shoe secured to said arm and adapted to engage the heel of a bobbin in said hopper and to eject it from its disc, an auxiliary arm, an auxiliary transfer shoe secured to said latter arm and adapted to engage said bobbin near its tip and to eject said tip from its disc, and a connection between said arms located outside of the space defined between said discs within the circle of the bobbin stations for operating said shoes in unison for bobbin transfer.

5. In a filling transfer apparatus for a loom, the combination comprising a rotary hopper having a pair of axially spaced rotary discs defining a circular series of stations for releasably holding the ends of a number of bobbins between said discs, with the bobbins at one end projecting outwardly beyond the corresponding disc, and a mechanism for transferring the bobbins successively from said hopper to a shuttle and comprising a main transfer arm located outside of the space between said discs, a main transfer shoe carried by said arm and adapted to engage the projecting end of a bobbin in said hopper, outside of the space between said discs and to eject it from its corresponding disc, an auxiliary transfer arm extending into the space between said discs, an auxiliary transfer shoe carried by said latter arm and adapted to engage the section of said bobbin between said discs near its other end and to eject it from the other disc, and means located outside of the space between said discs connecting said arms for transfer operation in unison.

6. In a filling transfer apparatus for a loom, the combination comprising a rotary hopper defining a circular series of stations for releasably holding the ends of a number of bobbins, and a mechanism for transferring the bobbins successively from said hopper to a shuttle and comprising a transfer arm, and means holding said transfer arm for extension into operative transfer position through the circle of the bobbin stations, said arm in said extended position blocking continuous rotation of said hopper, said holding means being releasable to permit said arm to be manually withdrawn from said extending operative position into inoperative non-blocking position outside said circle.

7. In a filling transfer apparatus for a loom, the combination comprising a rotary hopper defining a circular series of stations for releasably holding the ends of a number of bobbins, and a

11

mechanism for transferring the bobbins successively from said hopper to a shuttle and comprising a transfer arm, a holder for said arm permitting movement of said transfer arm under manual control selectively into extended operative transfer position through the circle of the bobbin stations, where it blocks continuous rotation of said hopper or into inoperative non-blocking position outside said circle, and means for operating said holder upon receipt of a transfer call, to move said arm for transfer.

8. In a filling transfer apparatus for a loom, the combination comprising a rotary hopper defining a circular series of stations for releasably holding the ends of a number of bobbins, and a mechanism for transferring the bobbins successively from said hopper to a shuttle and comprising a transfer arm, a holder for said arm permitting movement of said transfer arm under manual control selectively into extended operative transfer position through the circle of the bobbin stations, where it blocks continuous rotation of said hopper or into inoperative non-blocking position outside said circle, a shaft supporting said holder with said transfer arm extending transversely of the axis of said shaft, and means for rotating said shaft partially upon receipt of a transfer call to move said arm for transfer operations.

9. In a filling transfer apparatus for a loom, the combination as described in claim 8, said transfer arm being movable endwise in said holder, and having a handle at its outer end by which said transfer arm may be pulled in said holder out of operative position, said holder having a spring-pressed latch for holding said arm in operative transfer position.

10. In a filling transfer apparatus for a loom, the combination comprising a rotary hopper having a pair of axially spaced rotary discs defining a circular series of stations for releasably holding the ends of a number of bobbins between said discs with the bobbins at one end projecting outwardly beyond the corresponding disc, and a mechanism for transferring the bobbins successively from said hopper to a shuttle and comprising a main transfer arm located outside of the space between said discs, a main transfer shoe carried by said arm and adapted to engage the projecting end of a bobbin in said hopper outside of the space between said discs and to eject it from its corresponding disc, an auxiliary transfer arm, means for holding said auxiliary transfer arm in extended operative position into the space between said discs where it blocks continuous rotation of said hopper, an auxiliary transfer shoe carried by said latter arm and adapted to engage the section of said bobbin between said discs near its end and to eject it from the other disc, said holding means being releasable to permit said auxiliary transfer arm and said auxiliary transfer shoe to be withdrawn into inoperative non-blocking position with respect to said hopper, and means connecting said holding means and said main transfer arm for transfer operation in unison.

11. In a bobbin transfer mechanism for a loom, the combination comprising a main transfer arm supported on a pivot mounting and having a shoe adapted to engage the heel of a bobbin in a rotary hopper for transfer purposes, an auxiliary transfer arm having a shoe adapted to engage the bobbin near the tip for transfer purposes, a pivot mounting for said auxiliary transfer arm separate from said first mentioned pivot mounting, and means for moving said arms angularly and in

12

unison about the axes of their respective pivot mountings for transfer operations.

12. In a bobbin transfer mechanism for a loom, the combination, comprising a main transfer arm supported on a pivot mounting and having a shoe adapted to engage the heel of a bobbin in a rotary hopper for transfer purposes, an auxiliary transfer arm having a shoe adapted to engage the bobbin near the tip for transfer purposes, a shaft to which said auxiliary transfer arm is secured for pivotal movement with said auxiliary transfer arm extending transversely of the axis of said shaft, a link connected to said main auxiliary arm and operable to move said main auxiliary arm about its pivot mounting for transfer operations, a crank arm rigid with said shaft, and connecting means between said crank arm and said link to operate said auxiliary transfer arm about its pivot axis in unison with said main transfer arm for transfer.

13. In a bobbin transfer mechanism, the combination described in claim 12, comprising a shuttle feeler device, a latch movable by said shuttle feeler device in and out of the path of movement of a loom lay, and a connection between said latch and said link for operating said link for transfer by the movement of the lay when engaging said latch.

14. In a bobbin transfer mechanism, the combination comprising a transfer arm carrying a shoe adapted to engage a bobbin in a hopper and transfer it therefrom to a shuttle, a shuttle feeler device having a feeler plunger, means for moving said feeler plunger into shuttle feeler position when transfer is indicated, a pivotally supported crank having a pair of arms, a latch movably carried on one arm of said crank, a connection between said latch and said plunger causing said latch to swing into the path of movement of the lay when said plunger is extended in shuttle feeler position and to swing out of said path when said plunger is withdrawn into inactive position, said latch extending in a direction and being operable to rotate said crank about its pivot support when said latch is engaged by the lay, and a connection between the other arm of said crank and said transfer arm for moving said transfer arm for transfer, as said crank is rotated about its pivot support, said first mentioned connection between said latch and said plunger being operable to move said latch out of the path of the lay when revocation of transfer is indicated by an improperly boxed shuttle.

15. In a bobbin transfer mechanism, the combination as described in claim 14, said first mentioned connection between the latch and the feeler plunger comprising a pair of longitudinally aligned link sections yieldably held together by a coil spring and permitted to be separated for extension purposes against the resistance of said spring.

16. In a bobbin transfer mechanism for a loom having a reciprocable lay, the combination comprising a transfer arm carrying a shoe adapted to engage a bobbin in a hopper and transfer it therefrom to a shuttle, a shuttle feeler, a latch supported for movement into and out of the path of the lay, a connection between said shuttle feeler and said latch for moving said latch into the path of said lay, when said feeler is extended into shuttle feeler position and for moving said latch out of said path, when said feeler is withdrawn into inactive position or has been moved by an improperly boxed shuttle during shuttle feeler operations, said connection comprising a link

13

having spring-pressed extensible sections permitting said link to be extended when said latch is engaged by said lay and is moved thereby, and means operable in response to the actuation of the latch by the engaging lay for effecting movement of said transfer arm for transfer operations.

17. In a bobbin transfer mechanism for a loom having a reciprocable lay, the combination comprising a transfer arm carrying a shoe adapted to engage a bobbin in a hopper and transfer it therefrom to a shuttle, a shuttle feeler device comprising a feeler plunger, a guide for said plunger having an elongated guide slot extending therewith, and a pin on said plunger projecting through said slot, a bell crank pivotally supported, a latch pivotally connected to one arm of said bell crank and movable into and out of the path of movement of said lay, an extensible link connection between said pin and said latch, for moving said latch into the path of said lay when said plunger is extended into shuttle feeler position and for moving said latch out of said path when

14

said plunger is withdrawn either because transfer has not been indicated or because of the action of an improperly boxed shuttle, said latch being mounted on said bell crank arm in position to rotate said bell crank about its pivotal support when said latch is engaged by said lay, and a connection between the other arm of said bell crank and said transfer arm for operating said latter arm for transfer upon rotation of said bell crank.

KAROL KULCZYCKI.
